UNITED STATES PATENT OFFICE

CALEB E. SUMMERS, OF PONTIAC, MICHIGAN, ASSIGNOR TO GENERAL MOTORS CORPORATION, OF DETROIT, MICHIGAN, A CORPORATION OF DELAWARE

PISTON

Application filed May 11, 1927. Serial No. 190,559.

This invention relates to pistons for internal combustion engines used on automotive vehicles.

It is the object of the present invention to construct a two-piece piston having a head portion of one kind of metal and a skirt portion of a different kind. The metal for the head portion is preferably one which is of relative light weight and which, at the same time, has a good thermal conductivity, while the metal for the skirt portion has relatively large wear resisting qualities and also a relatively low thermal coefficient of expansion. For the head of the piston I preferably use 15 aluminum and for the skirt portion a properly alloyed and heat treated steel is to be preferred.

Inasmuch as two kinds of metal are used, they will have different coefficients of expansion and I accordingly design the two parts so that their meeting edges will form an inclined surface and they will be so proportioned that this meeting surface will be in firm contact at all times, regardless of the 25 temperature to which the piston is subjected during the operation of the engine.

The head of the piston is provided with two downwardly projecting webs, at the end of which I form bearing boxes for the reception of the pin of the connecting rod. The skirt portion is provided with openings having boss formations which are concentric with the bearing boxes and into which the ends of the piston pin is received.

35 The head of the piston is cast and in order to unite the skirt portion to the head portion I provide two brackets about which the head is cast so that they form a substantially integral structure therewith. These brackets project laterally from the bearing boxes and have flanged ends to which the skirt portion is secured, for example, by welding.

45 As a modification I may cast the head portion into the skirt portion and provide flanges on the skirt around which the metal of the head may be cast in order to hold the two parts rigidly together. I may also provide dovetailed formations on parts of the skirt 50 and into which formations the cast metal may

flow in order to secure a more intimate connection between the head and skirt portion.

The invention is disclosed in the accompanying drawing in which:

Fig. 1 is a view in elevation of a piston 55 constructed in accordance with my invention with parts shown in section for purposes of clearer illustration.

Fig. 2 is a section on the line 2—2 of Fig. 1.

Fig. 3 is a section on the lines 3—3 of Figs. 60 1 and 2.

Fig. 4 is a sectional view of a modification.

Fig. 5 is a sectional view on the line 5—5 of Fig. 4.

Referring to the numbered parts on the 65 drawing, 10 indicates my improved piston as a whole, 11 is the upper part or head portion, and 12 the lower part or skirt portion.

The head is cast of a metal which preferably has a good thermal conductivity and at 70 the same time is relatively light in weight, aluminum being preferred. This head has the usual grooves 13 for the reception of the conventional piston rings and is also provided with two downwardly projecting webs 75 14 and 15 connected by a bridge or rib 16 which strengthens the entire structure. The head is hollow, except for the rib 16, which makes for a very light structure.

The ends of the webs 14 and 15 terminate 80 in enlarged portions forming boxes 17 and 18, having openings 19 and 20, respectively, for the reception of the pin which pivots the piston rod to the piston 10.

By referring to Figs. 1 and 2 it will be 85 noted that the head has an inclined surface at 21 which extends around the periphery and the purpose of which will be later described.

At the time of the casting of the cylinder 90 head 11 a pair of brackets 22 and 23 are properly positioned in the mold so that the box portions at the ends of the webs 14 and 15 will embed the brackets so as to make them substantially integral with the piston head. 95 These brackets have central openings as at 24 conforming to the openings 19 and 20 of the boxes 17 and 18 to allow for the passage of the connecting bolt and these openings are flanged so as to obtain a close contact be- 100

tween the head and the brackets and to more securely hold the parts together. These brackets are flanged at their outer ends as at 25, for a purpose which will be later set forth.

5 The second part of the piston comprises the skirt portion 12, which is preferably made from a blank and later rolled into its finished shape for assembly with the head portion. The skirt has the stiffening ribs 26 and at its 10 meeting place with the head 11 it has an inclined flanged edge 27, complementary to the inclined edge 21. The construction of the head 11 and skirt 12 is such that when the heating of the piston takes place during the 15 operation of the engine, the difference in the coefficients of expansion of the two metals is such that a tight contact between the surfaces as 21 and 27 will be maintained at all times.

At the meeting edges of the skirt portion 20 when rolled together I preferably provide tabs 28 which may be welded together to hold the skirt in its circular form. The entire seam may also be welded if desired.

The skirt is attached to the head structure 25 by means of the flanges 25 on the ends of the brackets 22 and 23. By referring to Fig. 3 it will be noted that these flanges conform to the circular shape of the skirt as shown at 29 and at which meeting surfaces the skirt 30 and bracket are united by any suitable means, welding being preferred.

The skirt is also provided with two openings 30 and 31, having inwardly extending bosses 32 and 33, which conform to and are 35 concentric with the openings 19 and 20 of the piston head 11. By referring to Figs. 2 and 3 it will be noted that there is a close contact as shown at 34 between the bosses 32 and 33 and the bearing boxes 17 and 18.

40 The species of Figs. 4 and 5 differs from that of Figs. 1 to 3 in that the head 11' is cast into the skirt portion 12'. The downwardly extending webs 14' are cast into the dovetailed portions 35 of inwardly bent tabs 45 36 on the skirt 12' to give a close contact and insure a more intimate connection between the head 11' and skirt 12'. In this species the bosses 32' and 33' are surrounded by the cast metal from the head 11' forming 50 a structure which is substantially integral and which is very rigid.

In all species, the bottom of the skirt portion is inturned as at 37, giving a rounded edge as shown at 39.

55 I claim:

1. In a piston, a head portion, bearing members in said head having bearing surfaces, a skirt portion abutting and forming a continuation of said head, and bosses on 60 said skirt in alignment with said bearing members, said bosses forming a continuation of the bearing surfaces.

2. In a two part piston, an upper part, a plurality of webs extending from said upper 65 part, bearing boxes at the end of said webs,

said boxes having bearing surfaces, a lower part surrounding said webs and bearing boxes, bosses on said lower portion concentric with said boxes, said bosses forming a continuation of said surfaces, and means to secure said parts together. 70

3. In a two part piston, an upper part, a plurality of webs extending from said upper part, bearing boxes at the end of said webs, 75 said boxes having bearing surfaces, a lower part surrounding said webs and bearing boxes, bosses on said lower portion concentric with said boxes, said bosses forming a continuation of said surfaces, means to secure said parts together, and a single inclined peripheral edge on each said head and skirt, 80 said edges complementary to each other and forming the sole peripheral contact.

4. In a two part piston, an upper part, a plurality of webs extending from said upper part, bearing boxes at the end of said webs, 85 said boxes having bearing surfaces, a lower part surrounding said webs and bearing boxes, bosses on said lower portion concentric with said boxes, said bosses forming a 90 continuation of said surfaces, means to secure said parts together, and a single inclined peripheral meeting edge on each of said head and skirt, said edges complementary to each other and forming the sole peripheral contact, 95 said inclined surfaces being such that the relative expansion of the metals of the head and of the skirt will keep the two parts in firm contact at all times.

5. In a two part piston, a skirt portion, 100 a head portion cast into said skirt portion, bearing portions formed on said head portion, and bosses and tabs on said skirt portion into which said head is cast, said bosses arranged concentric with said bearing portions and said tabs positioned circumferentially below and spaced from said bosses. 105

6. In a piston, a plurality of separate brackets, a head portion cast about a portion of said brackets, a skirt portion formed separate from said brackets and forming the lower end of said piston, said skirt portion secured to the ends of said brackets, said bracket portion in said head having a flanged or bent edge. 110

7. In a piston, a plurality of separate brackets, a head portion cast about the mid portion of said brackets, a skirt portion formed separate from said brackets and forming the lower end of said piston, said skirt portion secured to the ends of said brackets, said brackets having their mid portions provided with bent edges to firmly hold them in the cast head and their ends flanged to afford a securing means between the piston and skirt. 120

8. In a piston, a cast head portion, an inclined or tapered peripheral or circumferential edge at the lower-most circumferential 130

portion of said head, a skirt portion secured to said head, and an inturned inclined flange on the upper end of said skirt, said flange abutting with and conforming to said inclined or tapered portion of said head.

- 5 9. In a piston, a cast head portion, an inclined or tapered peripheral or circumferential edge at the lowermost circumferential portion of said head, a skirt portion, a plurality of brackets having said head portion cast about their mid portions, said brackets extending away from their cast connection and secured to said skirt at their ends, and an inturned inclined flange on the upper end of said skirt, said flange abutting with and conforming to said inclined or tapered portion of said head.

In testimony whereof I affix my signature.
CALEB E. SUMMERS.
